Primary Examiner—Brian N. Vinson
Attorney, Agent, or Firm—Kenyon & Kenyon[57] **CLAIM**

The ornamental design for high leverage shears, as shown and described.

DESCRIPTION

FIG. 1 is a right side elevational view of high leverage shears showing our new design, the left side being a mirror image of that shown;

FIG. 2 is a top plan view thereof, the bottom being a mirror image of that shown;

FIG. 3 is a front elevational view thereof;

FIG. 4 is a rear elevational view thereof;

FIG. 5 is a right side elevational view of an alternate embodiment thereof, the left side being a mirror image of that shown and the rear being identical to that shown in FIG. 4, except for the degree to which the angled blade portion is visible; and

FIG. 6 is a front elevational view of the embodiment of FIG. 5.
